UNITED STATES PATENT OFFICE.

EZRA W. HASENPFLUG, OF GENEVA, OHIO, ASSIGNOR TO THE CHAMPION SAFETY LOCK COMPANY, OF GENEVA, OHIO, A CORPORATION OF OHIO.

HINGE.

1,145,241.

Specification of Letters Patent.

Patented July 6, 1915.

Application filed July 23, 1909. Serial No. 509,134.

To all whom it may concern:

Be it known that I, EZRA W. HASENPFLUG, a citizen of the United States of America, and a resident of Geneva, in the county of 5 Lake and State of Ohio, have invented certain new and useful Improvements in Hinges, of which the following is a specification.

My invention relates to improvements in 10 spring hinges, and has for its object the cheapening and strengthening of a hinge; the provision of spring-retaining means, and the construction of a spring hinge in such manner that the pin may be readily 15 removed to separate and reassemble the hinge sections.

In prior hinges of this class, it has been found necessary either to employ a separately pivoted member for retaining the 20 spring under tension, which is interposed between the two hinge sections, or the spring is released each time the pin is removed. The former type of hinge involves a somewhat cumbersome construction, while the 25 sections of the latter type are not readily united when secured in position, by reason of the necessity for first placing and maintaining the initial tension upon the spring.

Again, with the parts stamped from sheet 30 metal, the bearing portions of the hinge for engaging the pin, ordinarily are restricted in size to the thickness of the metal employed for the stamping; while the pin is relied upon not only for pivoting the hinge 35 sections, but for retaining the spring in place, thus making the structure integral and non-separable. Thus, in my improved device, the removable or separable leaf of the hinge itself, is so constructed as to maintain the spring mounted thereon, under normal 40 tension, and always ready to be assembled.

Having these features and requirements in mind, I have devised a cheap and simple 45 hinge attaining certain distinct advantages over the prior structures with which I am acquainted. I may best describe the improvements in connection with the accompanying drawing, wherein:—

50 Figure I is a front view of a hinge embodying my invention. Fig. II illustrates a slightly modified form thereof. Fig. III is a cross-section on line III—III, of Fig. I. Fig. IV is an end view of the hinge shown 55 in Fig. II. Fig. V is a side view of the

spring-retaining section. Fig. VI is a similar view of the co-acting hinge section. Fig. VII shows the loose pin for connecting the hinges. Fig. VIII is a detail illustrating a modification of the spring retaining means; 60 and Fig. IX is another detail indicating the ready separation of the hinge sections by the removal of the pin.

Throughout the several figures of the drawings, I have employed the same character of reference to designate similar parts. 65

In the types of hinge herein shown, the leaves are stamped from sheet metal, and the knuckles or pivotal joints are formed by lugs turned up either interiorly or exteriorly 70 of the blank, while said lugs are in turn flanged, not only to secure extended bearings for the pin or pintle, but for retaining the spring in place, as well. In addition, it will be noted that the spring section of the hinge 75 lies interiorly of the supporting section, and carries a suitable lug for retaining the spring substantially under normal tension, independently of the supporting section.

Referring now to specific embodiments of 80 my invention; that of Fig. I comprises a spring-section *a* and supporting-section *b* respectively adapted to be screwed to the door and the door frame. Two lugs *a'* *b'* are bent up interiorly at either end of said 85 sections for the purpose of forming the knuckle of the hinge. The lugs *a'* are centrally punched or flanged to produce in-turned ferrules *a''*, which extend within and serve to retain the spring *c* in place. On the upper lug there is also provided an outwardly extending lug *a²*, which extends behind the protruding end of the spring and maintains the same substantially under normal 90 tension, so that the hinge sections may 95 readily be supported and assembled. Similarly, the lugs *b'* are provided with outwardly extending ferrules *b''*, which with the ferrules *a''* afford relatively extended bearing surfaces for the removable or loose 100 pin *d*. The leaves of the hinge are suitably perforated with screw holes *e* and are ribbed, both for the purposes of ornamenting and strengthening the hinge sections.

Little explanation is necessary for the 105 purpose of understanding the construction of Fig. II, which closely resembles the one already described. It may be pointed out, however, that the lugs *a'* *b'* are bent up exteriorly of the hinge blank proper, and the 110

- screw holes *e* and ribs *f* are a little more advantageously positioned in or near the extremities of each hinge section; better adapting said hinge for certain purposes.
5. In the modification of Fig. VIII, moreover, the construction already described is followed out with the addition of a partial overturned flange *a'*, adapted to engage the exterior of a larger and heavier spring than those shown in the foregoing figures, for the purpose of retaining it in place. This flange, of course, will be provided above and below, and may be used alone or in addition to the in-turned ferrule *a''*.
10. It will now be understood that a door mounted with my improved spring hinges, may be readily removed upon taking out the removable pins, and, as indicated, this is particularly desirable with screen doors, which require storing during a large portion of the year. Again, the expanded or extended bearings afforded for the stamped metal hinge by the integral ferrules or flanges *a'' b''*, greatly improve a device of this class, while the spring retaining means found in the in-turned ferrules, the lug *a'*, and the lip *a''*, are practically essential in equivalent form, to a removable or loose-pin spring-hinge.
15. Having now described certain embodiments of my invention, I claim and desire to secure by Letters Patent, the following:—
1. The combination in a hinge, with two leaves having stamped metal lugs extending at right angles therefrom; the said lugs having ferrules or flanges formed respectively upon the opposite sides thereof, of a pintle extending through said ferrules and having bearing surfaces therein, substantially as set forth.
20. 2. In a separable spring hinge, the combination with two hinge sections formed of stamped metal, having co-acting lugs bent at right angles from the bodies thereof, and a rearwardly-positioned retaining-lip on one of said sections, of a spring mounted upon the latter section and retained under normal tension by said lip, and a removable pintle pivotally uniting said lugs for assembling the hinge sections, substantially as set forth.
25. 3. In a stamped metal hinge, the combination with two integral hinge sections, comprising co-acting leaves having pivoting lugs bent substantially at right angles thereto in two different planes of engagement, fitting one within the other; the said lugs having ferrules respectively formed thereon extending on either side of said planes of engagement to form widely separated bearings, of a pintle extending through said ferrules and pivotally mounting said hinge sections, substantially as set forth.
30. 4. In a separable spring hinge, the combination with two hinge sections, of a spring mounted upon one of said sections; the latter being shaped to engage the interior and terminals of the spring and maintain the spring under normal initial tension when thus mounted, and a removable pintle for separably and pivotally uniting said hinge section with the other section, substantially as set forth.
35. 5. In a spring hinge, the combination with two separable hinge sections, of a spring permanently mounted upon one of said hinge sections; the latter having integral engaging parts for retaining the spring under normal tension, and a removable pintle for separably mounting the hinge sections, substantially as set forth.
40. 6. In a spring hinge, the combination with two separable hinge sections, one of which is formed with integral engaging parts comprising interiorly engaging ferrules and a lip for maintaining the spring under normal initial tension, a coiled spring permanently mounted in the latter section with one end extended in position to be engaged by the opposing hinge section, and a removable pintle for separably connecting said hinge sections, substantially as set forth.
45. 7. In a spring hinge, the combination with two separable hinge sections formed of stamped metal and having lugs bent at right angles from the bodies thereof, spring-mounting members and a retaining lip upon one of said sections for maintaining the spring under tension, of a spring mounted under normal initial tension upon said section and having an extended end for engaging the other section, and a removable pintle passing through the lugs and pivotally mounting the hinge sections, substantially as set forth.
50. 8. In a spring hinge, the combination with two stamped metal sections or leaves having rectangular lugs respectively formed thereon, interiorly engaging ferrules formed on the lugs of one hinge section together with a lip for retaining the spring under substantially normal tension, of said spring mounted between the lugs and ferrules of one of said sections and retained under tension by the lip, and a removable pintle extending through said lugs and ferrules for pivotally connecting the hinge sections, substantially as set forth.
55. 9. In a spring hinge, the combination with two integral stamped metal hinge sections having co-acting lugs respectively bent therefrom above and below, interiorly extending ferrules formed in the lugs of one of said sections, and a retaining lip provided on the same section, of a coiled spring permanently mounted upon the latter section between the ferrules and retained under tension by the lip with its end extended in position to engage the other section, and a removable pintle extending through the

lugs and ferrules, for pivotally uniting the hinge sections, substantially as set forth.

10. In a spring hinge, the combination with two hinge-sections, comprising co-acting leaves having lugs stamped or bent at right angles thereto; the lugs of one fitting between those of the other and ferrules being integrally formed upon the inner lugs, a spring retained in position by said ferrules, and a pintle extending through said lugs, substantially as set forth.

11. In a separable spring hinge, the combination with two hinge sections, of a spring

permanently mounted upon one of said sections under substantially the normal or initial tension; the latter section having a retaining lip substantially in the plane of the other section, and a removable pintle for separably and pivotally uniting said hinge sections, substantially as set forth.

Signed at Cleveland, Ohio, this 15th day of July, 1909.
